UNITED STATES PATENT OFFICE.

THOMAS J. RUDESILL, OF MADISON, WISCONSIN, ASSIGNOR TO SCANLON-MORRIS CO.,
OF MADISON, WISCONSIN.

CHART HOLDER.

Application filed October 7, 1922. Serial No. 593,157.

To all whom it may concern:

Be it known that I, THOMAS J. RUDESILL, a citizen of the United States, residing at Madison, in the county of Dane and State 5 of Wisconsin, have invented certain new and useful Improvements in Chart Holders, of which the following is a specification.

My invention relates to chart holders used in hospitals; and the objects of my 10 invention are, first, to construct a chart holder in which the weight of the holder and contents will increase the pressure of the clip when hanging from a hook or the like; second, to construct the device of metal 15 preferably of aluminum, except a spring and the rod upon which it is mounted.

I attain these objects by the mechanism shown in the accompanying drawing in which—

- 20 Fig. 1, is a view of the top edge;
Fig. 2, is a front elevation;
Fig. 3, is a side elevation.
Similar numerals refer to similar parts throughout the several views.
- 25 The back 1 is formed from a sheet of 16 gauge aluminum with the lower corners rounded and a portion of the sheet removed from the upper edge at the center and outer corners, so that the remaining metal may 30 be turned around a fulcrum pin 2 forming knuckles 3. A clip is provided adapted to be mounted on the fulcrum pin between the knuckles and held in contact with the back by means of a torsion spring 5 which 35 is disposed around the pin 2 with the ends thereof extending a distance beyond the same. One end 6 is seated in a groove 7 on the under side of the rear member 8 of the clip and the other end 9 rests under 40 the top edge of the back. The clip is formed of a top member 4 of sheet metal bent downward across the front edge 10

thence extends backward a distance parallel to the back 1 thence downward approximately at right angles to a point 45 slightly beyond the back thence backward in alignment with the back and provided with a hole 11. Ears 12 depend from the plate 4 and are drilled, forming bearings by which the clip is mounted on the pin. 50 Buttons 13 are secured under the two front corners of the plate 4 by screws 14.

It is obvious that by the novel construction and mounting of my clip I attain an object heretofore overlooked in the design- 55 ing of chart or paper holders, as it can be seen by reference to Fig. 3, that by suspending the holder from the hole 11, over a pin 15, the weight of the holder and contents will force the buttons 13 towards the 60 back 1 and securely grip papers between the two, regardless of any assistance from the spring 5.

Having thus described my invention, I 65 claim:

In a chart holder, a back and knuckles formed from sheet aluminum, a pin disposed through the knuckles, a torsion spring mounted on the pin between the knuckles, one end of the spring resting against the 70 back, and the other disposed in a groove on the under side of a clip, in combination with a clip so mounted on the pin that the weight of the holder when suspended from a hook in the wall, will force the front edge 75 of the clip towards the back of the holder, as described and explained.

In testimony whereof I affix my signature in the presence of two subscribing witnesses.

THOMAS J. RUDESILL.
